(57) **CLAIM**

The ornamental design for a jacket with saddlebag, as shown and described.

DESCRIPTION

FIG. 1 is a front view of a jacket with saddlebag showing the new design;

FIG. 2 is a rear view of FIG. 1;

FIG. 3 is an enlarged right side elevation view thereof; the saddlebag shown removed from the jacket; and,

FIG. 4 is an enlarged left side elevation view thereof, the saddlebag shown removed from the jacket.

The broken lines in FIGS. 1 and 2 represent the portions of the jacket with saddlebag, which form no part of the claimed design.
